UNITED STATES PATENT OFFICE.

WILFRED LEWIS, OF HAVERFORD, PENNSYLVANIA, ASSIGNOR TO THE TABOR MANUFACTURING COMPANY, OF PHILADELPHIA, PENNSYLVANIA, A CORPORATION OF PENNSYLVANIA.

FLASK-CLAMP FOR ROLL-OVER MOLDING-MACHINES.

1,245,113.

Specification of Letters Patent. Patented Oct. 30, 1917.

Application filed April 10, 1917. Serial No. 160,907.

To all whom it may concern:

Be it known that I, WILFRED LEWIS, a citizen of the United States, and a resident of Haverford, in the county of Montgomery and State of Pennsylvania, have invented a certain new and useful Flask-Clamp for Roll-Over Molding-Machines, of which the following is a specification.

The principal object of the present invention is to provide a convenient, efficient, reliable and easily and quickly operable flask-clamp for securing flasks to the frames of roll-over molding machines, of which there are a great variety.

15 The invention will be claimed at the end hereof but will be first described in connection with the embodiment of it chosen for illustration in the accompanying drawings, in which—

20 Figure 1, is a side view illustrating at the right thereof and in open position, a clamp embodying features of the invention and at the left thereof in dotted lines, the clamp in closed position.

25 Fig. 2, is a view, partly in section, showing a clamp embodying features of the invention, and

Fig. 3, is an end view of the clamp.

The molding machine shown in the drawings is merely typical of a roll-over molding machine and needs no particular description further than to say that 1 is the roll-over frame which, as is well known, is turned by suitable mechanism and in turning carries the flask with it. 2 and 3 are strap elements, shown as arranged in pairs, and they are connected with the roll-over frame and since they are arranged in pairs a description of one of each pair will for most purposes be sufficient. The strap element 2 is immovably connected with the roll-over frame. As shown in Fig. 1 this is accomplished by bolting portions of it, as at 4, to a cross-shaft 5 carried by the frame but

45 this connection is merely illustrative. The strap element 3 is turnably connected with the roll-over frame 1 so that it may occupy the position shown at the right-hand side of Fig. 1, as well as the position shown in Fig. 2. 6, are disks turnably mounted in the frame and 7 is a shaft eccentrically mounted in the disks. To this shaft 7 is connected a handle 8 so that when the

handle 8 is turned, as indicated in Fig. 2 by full and dotted lines, the eccentrics are 55 turned in their bearings in the frame 1. 9, are sleeves mounted on the shaft 7 so as to turn thereon and to these sleeves the strap elements 3 are connected as at 10. The strap elements are shown as provided with 60 projections 11, arranged at different distances along the strap elements. The flask holding rails 12 are notched at their ends so as to straddle the strap elements and extend under the projections 11 so as to be 65 engaged thereby. Use is made of one or another of the elements 11 according to the depth of the flask α . The handle 8, or more accurately the frame thereof, is provided with ledges or shelves 13, by means of which 70 the rails 12 when not in use are supported between the handle frame and the strap elements 3 as shown in Fig. 1.

In use the flask α is mounted on the frame 1 and the rails 12 are properly applied to 75 the strap elements underneath their appropriate projections 11 with the handle 8 in its lowermost position as shown by full lines in Fig. 2; thereupon the handle is turned upward as shown in Fig. 2, thus causing the 80 disks to turn and in doing so to pull down the strap elements 3 and so clamp the flask firmly to the frame 1. After the frame 1 and flask have been turned over, the handle 8 is turned upward from the position shown 85 in dotted lines in Fig. 1, thus shifting the strap elements 3 away from the frame 1 and freeing them from the rails 12 sufficiently to permit of the strap elements being turned clear of the rails in order to un- 90 clamp the flask.

It will be obvious to those skilled in the art that modifications may be made in details of construction and arrangement without departing from the spirit of the invention, which is not limited as to those matters nor to the particular form of roll-over machine illustrated nor otherwise than as the appended claims and the prior state of the art may require.

100 What I claim is:

1. A flask-clamp for roll-over molding machines comprising the combination of a roll-over frame, strap members each permanently carried by the frame, a flask holding rail adapted for detachable connection

with two of the strap members, and an eccentric connection for tightening and loosening the clamp.

2. A flask-clamp for roll-over molding machines comprising the combination of a roll-over frame, strap members of which one is immovably connected with the frame, turnable disks mounted on the frame and to which the other strap member is eccentrically pivoted, and a detachable flask holding rail adapted to coöperate with said strap members.

3. A flask-clamp for roll-over molding machines comprising the combination of a roll-over frame, strap members constituting permanent parts of the frame and of which one is immovably and the other turnably

connected to the frame, a flask holding rail adapted for detachable connection with each of the strap members, and means for tightening the clamp.

4. A flask-clamp for roll-over molding machines comprising the combination of a roll-over frame, strap members of which one is attached to the frame, a turnable disk mounted on the frame and to which the other strap member is eccentrically pivoted, a flask holding rail detachable in respect to the strap elements, and a handle adapted for turning the disk and provided with means for supporting the rail between it and the turnable strap element when they are not in use, substantially as described.

WILFRED LEWIS.
